UNITED STATES PATENT OFFICE.

PAUL E. HECK, OF PHILADELPHIA, PENNSYLVANIA.

JEWELER'S FORMING AND CLAMPING DEVICE FOR FINGER-RINGS.

Specification of Letters Patent. Patented Feb. 15, 1921.

1,368,797.

Application filed November 14, 1919. Serial No. 338,072.

To all whom it may concern:

Be it known that I, PAUL E. HECK, a citizen of the United States, residing at Philadelphia, in the county of Philadelphia and State of Pennsylvania, have invented new and useful Improvements in Jewelers' Forming and Clamping Devices for Finger-Rings, of which the following is a specification.

The invention relates to jewelry and has for an object to provide a combined base forming, clamping and holding device for use in securing articles of jewelry such as finger rings and the like in position to be operated upon.

The invention comprehends among other features the provision of a simple device which in the mounting of a ring in position to be operated upon, molds the usual base or holding substance such as shellac into the desired shape so that upon the hardening of the shellac and its subsequent use with my device, the ring will be conveniently held in position to be operated upon and can be quickly and conveniently adjusted or positioned at various angles to the operator, permitting him to efficiently carry on such mounting or repair work as may be necessary on the article of jewelry.

In the further disclosure of the invention, reference is to be had to the accompanying drawings constituting a part of this specification in which similar characters of reference denote corresponding parts in all the views, and in which,—

Figure 1 is a perspective view of the device.

Fig. 2 is a vertical longitudinal sectional view taken through the device showing a ring mounted therein, and

Fig. 3 is a horizontal sectional view taken on the line 3—3 in Fig. 2.

Fig. 4 is a fragmentary side elevation of a slightly modified form.

Referring more particularly to the views I provide a body 10 having a portion thereof formed to provide a suitable handle or holder 11 with an upper part of the body 10 provided with a cut away portion 12 and an extension forming a jaw 13, this jaw being preferably termed a stationary jaw. The numeral 14 indicates a movable jaw which is adapted to be disposed in opposed relation to the stationary jaw as shown, to be moved backwardly and forwardly in the cut-away portion thereon, a clamping member or screw 15 being provided to pass

through the movable jaw 14 and extend into the stationary jaw 13 so that upon actuating said screw, the movable jaw will be moved toward or away from the stationary jaw. The jaws are maintained in substantially parallel relation by suitable guide pins 16 which are arranged to project from the face of the stationary jaw and loosely pass through openings or cross passages 17 in the movable jaw and an adjusting screw 18 is provided, the latter being threaded in the movable jaw and having its inner end adapted to abut against the face of the stationary jaw, said latter mentioned screw being provided for purposes of fine adjustment of the movable jaw relative to the stationary jaw or the parts that may be clamped in and between the jaws.

The face of the stationary jaw is provided with a depression or recess 19 which is of a hexagonal configuration and similarly the movable jaw 14 has a depression or recess 20 of a similar nature and in immediate opposed relation to the recess 19, it being of course understood that these recesses may be of either of hexagonal or octagonal formation. The numeral 21 indicates a finger ring and the numeral 22, the plastic base, said base consisting of a quantity of shellac which is preferably first heated and then pressed within the confines of the band of the ring after which this base carrying the ring is arranged between the jaws 13, 14, and the movable jaw is actuated to bring about a clamping operation causing the soft and pliable shellac to have portions thereof pressed into the recesses 19, 20 and assume the configuration of the recesses so that when the shellac hardens the body of the shellac will be formed with opposed hexagonal knobs 24, 24, brought about by the pressing of the shellac into the recesses 19, 20, respectively. The ring will now be held securely by the base which in turn is secured between and by the clamps and of course the ring being held rigidly upon the base, the base in turn will be held from turning by reason of the hexagonal knobs fitting into the hexagonal recesses. The operator now holds the device in one hand by firmly grasping the handle or holder 11 and then with the other hand, he manipulates the tool or tools with which he operates upon the ring.

By having the recesses 19, 20 of a hexagonal configuration and consequently having the formed knobs of a similar configura-

tion, the operator when he finishes working on the ring from one angle can unclamp the base and then position the same at a different angle, reclamping the knobs in the recesses thus permitting the operator to safely work upon the ring from different angles while holding the device substantially in the same position in the hand, thus obviating the usual danger of the tool slipping on the delicate mountings of finger rings and which ordinarily is due to the insecure clamping of the rings in working position and oftentimes results in great damage to valuable stones and settings.

15 By reference to Fig. 4 it will be seen that instead of having the recesses 19, 20, formed in the body portions of the stationary and movable jaws 13, 14, I may face the jaws with plates 13^a, 14^a, the plates having cut out portions 19^a, 20^a, which will form recesses.

It should also be noted that although I mention shellac as the material employed in forming the base, I may also employ any suitable form of cement or other material which when heated will become plastic so that it can be worked into a desired shape or configuration which will be maintained upon the subsequent hardening of the material.

From the foregoing description it will be seen that the device described consists of few and simple parts; that the same is not merely a holder for holding a ring in position to be worked upon, but that it also constitutes a means for forming a base, which in turn supports and carries a ring and it will be clearly understood that although in the drawings and this specification, I have described a particular form of my article, that various slight changes may be made without departing from the spirit of the invention, the scope of which is defined in the appended claims.

45 Having described my invention, I claim,
1. A device of the character described comprising a holder formed as a clamping device including jaws, the jaws being formed in their confronting faces with angular 50 sockets, in combination with a jewelry holding means formed as a base of plastic material within which the jewelry is embedded, the base being initially compressed between the jaws whereby to force the base into the 55 sockets.

2. A device for forming a plastic base for jewelry and for clamping and supporting the base, comprising a holder, a jaw on the

holder, a second movable jaw, means for relatively adjusting said jaws to clamp the 60 plastic base therebetween, there being sockets formed in the jaws to receive portions of the plastic material in the base and hold the same during the clamping action to form knobs corresponding with the sockets for the 65 rigid support of the base between the jaws upon subsequent hardening of the plastic material.

3. In a device for forming a plastic base for supporting jewelry and for clamping the 70 base, a plurality of jaws, each having a flat face provided with a recess of a hexagonal configuration and means for moving said jaws into and out of clamping positions, the plastic base carrying the jewelry being 75 adapted for interposition between the jaws to be clamped thereby and force portions of the material thereof into the recesses to form hexagonal knobs corresponding with the recesses, securing said base thereby 80 against movement relative to said jaws when the same are arranged in clamping relation with the base and thereby holding said jewelry in position to be operated upon.

4. A device for forming a plastic base for 85 jewelry for the latter to be subsequently adjustably mounted, comprising clamping members and sockets associated with said clamping members and having angular surfaces for the reception of portions of the 90 plastic base to mold the latter and form similar angular surfaces thereon so that the jewelry carried by the plastic base, when the latter subsequently hardens can be held by said clamping members and adjusted at 95 various angles thereto.

5. A device of the character described comprising a holder formed as a clamping device including jaws formed in their confronting faces with angular sockets, in combination with a jewelry holding means including a member of angular shape adapted for conforming engagement within said sockets.

6. A device of the character described 105 comprising a holder formed as a clamping device including jaws provided in their confronting faces with angular sockets, in combination with a jewelry holding means formed as a base of plastic material within 110 which the jewelry is embedded, the base being shaped to fit conformingly within said sockets.

In testimony whereof I affix my signature.

PAUL E. HECK.
